JOINT FOR WIRE FABRIC

Fred Crossman, Shaker Heights, Ohio, assignor
to The Lindsay Wire Weaving Company, Cleve-
land, Ohio, a corporation of Ohio

Application February 15, 1934, Serial No. 711,346

2 Claims. (Cl. 245—10)

This invention relates to a joint for wire fabrics. It is particularly adapted for use in making a seam in a Fourdrinier wire and has for one of its objects, the provision of a seam that will provide a strong joint between the ends of the fabric without the necessity for the use of a lacing wire.

One method heretofore devised for such purpose has utilized a thin strip of fusible metal that has been placed between the ends of the fabric and has been melted by the application of heat to effect the union. Such method has resulted in a joint between the ends of the fabric, but the joint has lacked sufficient strength to make it practical. This is due to the fact that it is extremely difficult to maintain the opposite ends of the same warp wire in direct alignment, prior to and during the application of heat to the fusible metal. Consequently, the ends are apt to be offset with the result that they are connected together only across a relatively small area.

A further object of my invention therefore, is to provide a seam which utilizes the feature of joining the ends of the fabric by the application of heat to an interposed fusible strip, but which in addition, provides an effective joint regardless of the fact that the ends of the warp wires may not be in exact alignment.

Referring now to the drawing, Fig. 1 is a plan view of a portion of a seam of a Fourdrinier wire that is made in accordance with my invention; Figs. 2 and 3 are sections taken on the correspondingly numbered lines in Fig. 1, and Fig. 4 is an enlarged sectional view taken through the interposed strand.

My invention is adapted for use in joining any two pieces of wire fabric, but as applied to a Fourdrinier wire, the warp wires are indicated at 10 and the weft wires at 11, while one end of the fabric is represented by A and the opposite end by B. In the preferred arrangement, the warp pickets of one end are substantially equal in length to those of the other end, and the opposing ends are placed on opposite sides of an interposed strand 15.

The strand 15 preferably comprises a laminated strip of fusible and non-fusible metal, and in the form illustrated it comprises an inner layer 20 of non-fusible metal, such as flat bronze wire, while

the outer layer 21 comprises silver solder, or other fusible metal, which is bent in the form of a U around the non-fusible strip. For 60 mesh wire, I prefer to use a non-fusible strip, which has a thickness of approximately .010 inches and a width of .025 inches. The fusible metal in turn may have a thickness of approximately .003 inches and a width sufficient to substantially enclose the strip 20, as is shown in Fig. 4.

After the strand 15 is placed between the ends 10 of the fabric, heat is applied to it, and at the same time, the ends are pressed towards each other. As a result of the application of heat, such as results from a blow torch, the strip 21 fuses and forms a coating that firmly unites the 15 ends of the warp pickets to the strip 20 and to each other. As a result, the strip 20 forms a bridge across the ends of the warp pickets, and thus, makes a strong connection or joint regardless of the fact that some of the warp wires may be out of alignment.

The utilization of a laminated strand, as described, enables heat to be applied simultaneously, if desired, along different parts of the seam, thus materially reducing the time for making the 25 seam, although in the preferred arrangement, the heat is applied progressively from one end to the other.

I claim:

1. A joint for a woven wire fabric having warp 30 wires and weft wires, comprising a relatively thin flat ribbon of non-fusible metal disposed between the ends of the fabric, and means for joining the ribbon to the warp wires on each side of the joint, said means comprising a layer of 35 fusible metal which embraces one edge and two opposite sides of the ribbon, and the ribbon being substantially equally spaced from the adjacent weft wires on each side thereof.

2. A joint for a woven wire fabric comprising 40 warp wires and weft wires, the warp wires having pickets of substantially the same length at each end of the fabric and a bridge piece connecting the ends of the pickets, and comprising a relatively thin flat ribbon of non-fusible metal 45 having a U-shaped coating of fusible metal extending around the ribbon.

FRED CROSSMAN.
